(57) **CLAIM**

The ornamental design for an amenity shelf, as shown and described.

DESCRIPTION

FIG. 1 is a front view of an amenity shelf;
FIG. 2 is a left profile view of the amenity shelf;
FIG. 3 is a back view of the amenity shelf;
FIG. 4 is a bottom view of the amenity shelf;
FIG. 5 is a top view of the amenity shelf;
FIG. 6 is a front perspective view of the amenity shelf; and,
FIG. 7 is a back perspective view of the amenity shelf.
The broken lines show portions of the amenity shelf that form no part of the claimed design.
